UNITED STATES PATENT OFFICE

167,093

FAN

Walter E. Moore, St. Louis, Mo., assignor to
Knapp-Monarch Company, St. Louis, Mo., a
corporation of Delaware

Application August 18, 1951, Serial No. 16,369

Term of patent 14 years

(Cl. D26—7)

To all whom it may concern:

Be it known that I, Walter E. Moore, a citizen of the United States and a resident of the city of St. Louis, State of Missouri, have invented a new, original, and ornamental Design for a Fan, of which the following is a specification, reference being had to the accompanying drawing, forming a part thereof, in which:

Figure 1 is a front elevational view of a fan, showing my new design, the rear elevation thereof being similar except for a solid disc in place of the wire guard.

Figure 2 is a side elevational view thereof, the reverse side being similar thereto; and

Figure 3 is a side elevational view as shown in Figure 2 with the fan adjusted to a different position with respect to its support.

I claim:

The ornamental design for a fan, substantially as shown and described.

WALTER E. MOORE.
